UNITED STATES PATENT OFFICE.

JAMES E. CONNOLLY, OF BALTIMORE, MARYLAND.

HANGER FOR COLLAPSIBLE CONTAINERS.

1,243,140.

Specification of Letters Patent. Patented Oct. 16, 1917.

Application filed December 2, 1916. Serial No. 134,648.

To all whom it may concern:

Be it known that I, JAMES E. CONNOLLY, a citizen of the United States, residing in Baltimore, Maryland, have invented certain new and useful Improvements in Hangers for Collapsible Containers, of which the following is a specification.

This invention relates to collapsible containers of the kind ordinarily used for holding and dispensing tooth paste, shaving cream, library paste and other substances in a plastic or pasty condition, and the object of the invention is to provide means for holding or suspending such containers when not in use in such manner that they will be kept clean, sanitary and always within convenient reach of the user.

Ordinarily containers of this kind when filled with tooth paste, for instance, are placed while not being used in a medicine closet with boxes, bottles and other articles, or are laid on a windowsill, washstand, or the like, and so become contaminated, and they also often fall to the floor and take up dust or other unsanitary matter. According to my invention I provide the containers with bails by means of which they may be hung on a hook, nail or the like driven into the wall, windowframe, or similar support.

In carrying out my invention I provide a bail preferably made of wire and pivotally connect it with the lower flattened end of the container. The bail is of such size and is so connected with the container that the latter can be wound within it from time to time during its use and when its contents are squeezed from it in the usual way.

The bail is pivotally connected with a metal clamp having jaws which engage the flattened end of the container and which are connected by a tubular joint to which the bail is applied. The clamp is by preference so made that it may be slid endwise onto the flattened end of the container and may in like manner be removed therefrom.

In the accompanying drawings—

Figure 1 is a perspective view showing a collapsible container of well known form equipped with a hanger made and attached in accordance with my invention and this figure of the drawings also shows how the hanger may be supported.

Fig. 2 is a front elevation of the parts shown in Fig. 1 and indicates how the

hanger may be attached to the container or detached therefrom.

Fig. 3 is a view on an enlarged scale and in section on the line 3—3 of Fig. 2.

Fig. 4 is a perspective view showing how the flattened container may be wound within the bail.

Fig. 5 is a view on an enlarged scale and in section showing more clearly some of the details of the invention.

Fig. 6 shows in section how the clamp may be applied to the container in which the flattened end is doubled but not reinforced by a permanently connected clamp.

Fig. 7 shows a further modification in which the flattened end of the container is provided with a permanently attached clamp and the bail is connected with a tubular portion of the clamp.

The container A is provided with a flattened portion a which is folded or doubled at a' in the usual way. In Figs. 1 to 5, a^2 indicates a reinforced clamp of soft sheet metal applied to the folded end of the container as is often done. The bail B is preferably made of wire and may be supported by a hook C or other suitable device. It is pivotally connected with a clamp D comprising jaws d and a tubular joint d' . The lower horizontal arms b of the bail extend into the tubular joint, as indicated in Fig. 2, and the jaws d engage the reinforced lower end of the container. The clamp is preferably attached to the container by sliding it endwise on the reinforced end thereof and the jaws are so shaped as to hold the container in such manner that the latter cannot be pulled downward out of the clamp, it being necessary to remove the bail from the hook when it is desired to use the paste.

The bail and clamp may be made and sold as a separate article of manufacture and readily applied to containers having folded ends of the kind shown. As the supply of paste is reduced the empty part of the container may be folded and wound around the clamp and within the bail in the manner indicated in Figs. 4 and 5.

It is not essential that the container be provided with the reinforcing clamp a^2 , as the bail and clamp of my invention may be applied directly to the folded or doubled end of the container as indicated in Fig. 6.

It will be observed that the jaws d are

curved and are so made as to engage the shoulders formed by the inner ends of the clamp a^2 , or the shoulder may be formed by the folded or doubled end of the container.

- 5 Fig. 7 shows a modification in which the flattened end of the container is reinforced by a clamp D' provided with a tubular part d^2 . In this case the bail B is provided with pointed arms b' which project into the tubular part b^2 and have a pivotal connection therewith. The bail being made of wire may be spread in such manner as to cause the arms b' to enter the ends of the tube and then assume the position shown in the

15 drawings.

The device made in accordance with my invention is extremely simple in construction, may be made at small cost, and is readily applied to collapsible containers of 20 standard makes and when so applied affords a secure and convenient means for suspending the container in a sanitary manner and always within convenient reach of the user.

I claim as my invention:

- 25 1. As an article of manufacture, a device

for dispensing the contents of collapsible tubes comprising a bail, and a tube-engaging means, a resilient clamp adapted to receive the end of the tube pivoted to said bail and about which the collapsible tube is adapted to be wound.

2. As an article of manufacture, a device for ejecting the contents of collapsible tubes comprising a normally closed clamp adapted to engage the closed end of said tube, 35 and a bail pivoted to said clamp, the width of the bail being greater than that of the clamp to permit the tube to be wound about said clamp.

3. As an article of manufacture, a device 40 for supporting collapsible tubes having a bail, a clamp rotatable on said bail and comprising a single sheet of spring metal folded upon itself to form a tubular bail-engaging portion, and elongated clamping 45 jaws having their ends diverging to form a rounded tube-engaging portion.

In testimony whereof, I have hereunto subscribed my name.

JAMES E. CONNOLLY.
